RAILWAY CAR

Otto Jabelmann, Omaha, Nebr.

Application February 27, 1939, Serial No. 258,831

2 Claims. (Cl. 105—2)

This invention relates to railway cars and particularly to the rear end car on streamlined high speed trains.

In streamlined trains the rear end car has been 5 tapered in order to reduce eddying and drag at the rear of the train. This imposes severe limitations in the capacity of the car and on the seating arrangement. The purpose of the present invention is to permit the use, at the rear end 10 of the rear car, of a more nearly conventional form, without entailing the usual severe losses caused by eddying and the suction effect of the train.

Another purpose of the invention is to minimize 15 rising air currents at the rear of the train.

To bring about the desired results, the car is given in plan a conventional or untapered form. The roof of the car in the central portion thereof is so constructed that it slopes downward very 20 gradually toward the rear and is curved or faired into the rear wall of the car. This taper, however, is wholly insufficient for streamlining, and to produce the desired action a false roof or cowling with entrance wind-scoop is mounted 25 above the rear half of the sloping portion of the car roof and is curved so as to discharge air directly across the rear end of the car in a generally downward direction.

The air scoop mounted at the entrance of the 30 duct between the roof and false roof, projects above the false roof, and to minimize eddying over the false roof a single narrow louver forming a sort of wing slot is mounted above the air scoop.

The purpose of the scheme is to deliver air to 35 the space at the rear of the train at a rate so rapid that the reduction of air pressure at the rear of the train is minimized, if not completely eliminated.

The duct above mentioned cannot conveniently 40 extend over the entire width of the car roof, but should be made as wide as possible with due regard to other factors. A plurality of flow defining vanes are provided and these are bent laterally at their discharge ends to distribute the 45 discharging air, so far as practicable, over the entire rear end area of the car.

A serious difficulty which has been encountered 50 with streamlined trains is the sharp rise of air flowing from beneath the car at the rear. This carries dust and gravel and is quite annoying, particularly at high train speeds. To prevent this, a louvered skirt structure depending beneath the floor of the car is mounted at the rear end of the car and is so arranged as to

impart to the discharging air a sharp downward component. This, together with the relief afforded by air delivered from the roof, substantially eliminates the rise of dust laden air at the rear of the train. 5

The invention will now be described in detail in connection with the accompanying drawing, in which—

Figure 1 is a plan view of the rear end of such a car, parts being broken away to show the flow 10 directing elements.

Figure 2 is an elevation of the same, with parts broken away.

Figure 3 is an elevation of the rear end of the car also with parts broken away. 15

In the drawing no attempt has been made to show the framing structure of the car or to illustrate windows or any accessory parts. The design of these features will conform to known practice. 20

In Figure 2, 6 represents the floor line of the car and 7 the roof line. In the rear portion of the car and for an overall width equal to about half the width of the car, the roof is depressed so as to taper downward toward the rear, as indicated at 8, and finally is faired or rounded as indicated at 9, into the rear wall 11 of the car. The effect is to produce a depressed channel whose side margins are indicated at 12 and 13 on Figure 1. 25

A series of vertical straight guide vanes are mounted in this trough as indicated at 14. They not only serve to permit air flow through the trough, but they also serve to support and connect with the car body a false roof 15 which is 30 spaced from the roof 8 and 9 and flares therefrom slightly, producing a downward curving duct which offers an air flow path of increasing transverse area. The false roof 15 does not extend forward to the commencement of the tapered portion 8 of the car roof, but extends only about halfway from the rear of the car to that point. It ends at the rear adjacent the lower margin of this curved or faired portion 9 of the roof. 35

At its forward end the false roof carries a flaring entrance wind scoop 16, and on this is mounted a small louver or vane 17. 40

The scoop delivers air to the passage between the car roof 8 and the false roof 15 and the vane 50 17 tends to smooth out the air flow over the top of the false roof 15. Because the air duct between the roof 8 and the false roof 15 does not extend the entire width of the car, the lower ends of the vanes 14 are bent laterally outward as 55

5 indicated at 18 in Figure 3. The purpose is to cause a part of the discharged air to flow outward toward the sides of the car and thus maintain as nearly as possible a normal atmospheric pressure over the entire rear end of the car body.

10 The vanes 14 are not needed at the center of the duct, where the discharge end of the duct extends continuously across the car, and the drawing indicates their omission. Such vanes should be used wherever needed to even the distribution of discharging air.

15 The downward flow of air tends to resist the rise of dust carrying air. However, to intensify this desirable effect the car is provided with a skirt 19 which extends below the car floor-line 6 and across the ends of the car. At the ends of the car it is provided with a number of louvers 21, three being shown, and these louvers incline downward toward the rear, so that air discharging 20 from beneath the floor of the car at the rear end of the car is given a sharp downward component which will further resist the rise of dust laden air at the rear of the train.

25 The described arrangement permits material increase in the floor areas of the last car of a streamlined train, and avoids the use of special seating arrangements which require special equipment and which unduly consume space. The performance from the standpoint of train 30 resistance is as good or nearly as good as that given by a conventionally streamlined train.

35 The performance, so far as dust effects at the rear of the train are concerned, is better than that of the conventional streamlined train.

35 For purposes of illustration, the one desirable arrangement has been shown, but particular cases

may require modifications and changes in detail, particularly in contours, width of duct, and location and form of the vanes. Consequently the description above given is intended to be illustrative and not limiting.

5

What is claimed is:

1. A rear end car for streamlined trains comprising a body substantially devoid of longitudinal taper, having an arched roof and having a substantially vertical closed rear wall; an air duct 10 formed by a depression in the center portion of the roof which deepens gradually toward the rear end and then curves into tangency with the rear wall; and a wind scoop structure overlying the rear portion of said duct and generally forming 15 a continuation of the arched roof but curving downward and flaring from the rear wall to form a canopy which serves to discharge air vertically downward across said closed rear end.

2. A rear end car for streamlined trains comprising a body substantially devoid of longitudinal taper, having an arched roof and having a substantially vertical closed rear wall; an air duct formed by a depression in the center portion of the roof which deepens gradually toward the 25 rear end and then curves into tangency with the rear wall; a wind scoop structure overlying the rear portion of said duct and generally forming a continuation of the arched roof but curving downward and flaring from the rear wall to form 30 a canopy which serves to discharge air vertically downward across said closed rear end; and flaring vanes in the discharge end of said duct serving to distribute the discharging air over substantially the entire area of said rear end.

35 OTTO JABELMANN.
